UNITED STATES PATENT OFFICE.

GEORGE BABARE AND NICHOLAS BABARE, OF TACOMA, WASHINGTON.

CALKING-TOOL.

1,291,358.

Specification of Letters Patent. Patented Jan. 14, 1919.

Application filed August 2, 1918. Serial No. 248,038.

To all whom it may concern:

Be it known that we, GEORGE BABARE and NICHOLAS BABARE, citizens of the United States of America, residing at Tacoma, in the county of Pierce and State of Washington, have invented certain new and useful Improvements in Calking-Tools, of which the following is a specification.

This invention relates to improvements in a calking tool.

The object of the invention is to provide a calking tool, by means of which calking material may be introduced into a hopper, and by reciprocation of a flat blade, associated with auxiliary devices a seam may be calked.

The invention also comprehends improvements in the details of construction and arrangement of parts which will be herein after described and particularly pointed out in the claims.

In the accompanying drawings:

Figure 1 is a top plan view of the improved calking tool.

Fig. 2 is a vertical central section of the same.

Fig. 3 is a detail perspective view of the flat blade.

Fig. 4 is a transverse section on the line 4—4, Fig. 1.

Fig. 5 is a detail perspective section of the head of the tool.

Figs. 6 and 7 represent respectively a side view and a vertical section of a modification.

The numeral 1 indicates a frame from one end of which extends a cylinder 2, adjacent which is a hopper 3, and from the hopper projects nose 4. The upper wall of the nose 4 is closed by an inclined top 5, which tapers toward the free open end, while the bottom of the nose is normally open.

Formed on the inside of the walls of the nose and the hopper are parallel grooves 6, which provide a guide way for a flat blade 7.

The blade 7 is provided with a stem 8, which finds a bearing in an opening 9, formed in one of the heads of the cylinder 2. The inner end of the stem is enlarged to form a head 10, which is provided with openings 11, to afford communication between the main portion of the cylinder and the space 12, between the stem 8, and the walls of said cylinder.

Fastened to the rear upper portion of the blade is a flat prong 14, provided on its forward end with teeth, indicated at 15.

Secured on the rear portion of the inside

of the inclined top 5, is a flat resilient member 16, the free end of which normally lies across the path of the free end of the blade.

Extending laterally from the nose is a pair 60 of spaced ears 17, to receive a guide wheel 18, which projects beyond the free open end of the nose, to guide the tool in the seam.

Projecting from the head 10 and into the cylinder 2 is a stem 20, and on the opposite 65 end thereof is a head 21, formed with an opening to afford communication with the cylinder each side said head, and fastened on the stem 20 in the cylinder between the heads 10 and 21 is a piston 22 against which compressed air acts to reciprocate the flat blade. 70

Surrounding the cylinder is a hand grip 25, which embraces an inlet pipe 26, one end of which fits in an opening 27, in one end of the cylinder, and the opposite end of which 75 fits in an opening 28, in the other end of said cylinder communicating with the opening 27, and the space 12, is a port 29, and from the opening 27 leads an exhaust port 30. Communicating with opening 28 and the space 31, between the head of the cylinder and the head 21 on the stem is a port 32, and also communicating with said opening 28, and the atmosphere is an exhaust port 34.

The pipe 26 is somewhat shorter than the 85 distance between the end walls of the openings 27 and 28, and near its ends it is provided with ports 35 and 36, adapted to register respectively with the ports 29 and 32 in the cylinder. 90

In operation, calking material is fed to the hopper, and compressed air is admitted to the pipe 26, and passes through the ports 36 and 32 and acts on the piston 22, to drive the blade forwardly, the air in space 12, being exhausted through ports 29 and 30 to the atmosphere. 95

The end of the blade 6, and the serrated edge of the prong 14, force the material forwardly in the nose 4. This action ejects the 100 material and drives it into the seam with a blow, the material in its forward movement forcing the yielding member 16, out of its path. By movement of the hand grip 25, in the opposite direction, the feed pipe 26 is 105 shifted and the ports 35 and 29 are brought into registry, and the exhaust port 30 is closed. This movement also uncovers ports 32 and 34 and vents the opposite end of the cylinder. The compressed air now passes 110 through ports 35 and 29, and acts on the opposite side of the piston 22, and the blade

is withdrawn to position to force forwardly another charge of calking material. When the blade is withdrawn, the free end of the resilient member 16, grips the material 5 against the top of the blade 7, and prevents the withdrawal of the charge rammed into the seam.

This operation is continued and the calking material is by successive blows driven 10 into the seam, and as the tool is laterally moved the roller acts to retain the charge and guide the tool along the seam.

Figs. 6 and 7, represents the invention as applied to a different form of pneumatic 15 actuating mechanism. In this form of the invention the head is the same as that previously described, and a spring 40 is employed to return the blade to normal position, while it is driven forwardly by the ordinary pneumatic means, indicated at 41. The air is 20 controlled by a finger trip 42, located on the handle 43.

What we claim is:—

1. A calking tool comprising a head 25 formed at its free end with a fixed tapered nose and in rear thereof with a hopper, the inner side walls of the nose structure having parallel grooves to form a guide way, a flat blade mounted to reciprocate in the parallel 30 guide way, means for reciprocating the blade, and a flat resilient member fastened at its inner end to the inner surface of the nose and extending entirely across the interior of the latter, and having its free end 35 corrugated and normally in the path of the end of the flat blade to engage the material on the upper surface of said blade to prevent said material being withdrawn from the seam after being rammed.

40 2. A calking tool comprising a head formed at its free end with a tapered nose open at its end and bottom and a hopper in rear thereof, a flat blade reciprocally mounted in the head and adapted to project beyond 45 the end of the nose in one movement

of its reciprocation, a flat serrated blade fastened to the surface of the first mentioned blade against the hopper, a resilient member secured at one end on the inside of the nose and having its free end normally projecting 50 in the path of movement of the first mentioned blade and adapted to coöperate with the latter in holding the calked material in the seam, a cylinder extending from the head and provided with ports, a stem extending 55 from the blade and into the cylinder the stem and the cylinder having heads, a hand grip on the cylinder and a supply pipe connected to the hand grip and, mounted to reciprocate on the cylinder and provided with 60 ports to coöperate with the ports in the cylinder to reciprocate the blade.

3. A calking tool comprising a head formed at its end with a fixed tapered nose open at its bottom, and free end, and formed 65 with parallel grooves to provide a parallel guide way, the head having an extended flared flange surrounding an opening which constitutes a hopper to supply the nose with calking material, a flat blade mounted to reciprocate in the parallel guideway and provided with a flat prong serrated at its free 70 end and normally projected upwardly and located in rear of the front edge of said blade, a resilient plate secured on the inside 75 of the nose in advance of the hopper and extending entirely across the interior of said nose, the free end of the resilient plate being corrugated and extending in the path of the end of the flat blade, means for reciprocating 80 the blade, a pair of ears extending laterally from the nose, and a roller mounted in the ears and projecting beyond the free end of the nose to hold the calked material in place after being rammed by the end of the blade. 85

In testimony whereof we affix our signatures.

GEORGE BABARE.
NICHOLAS BABARE.
